CLAIM

The ornamental design for a storage locker as shown and described.

DESCRIPTION

FIG. 1 is a top, front, left perspective view of a storage locker showing our new design, shown in an open position; FIG. 2 is a top view thereof;

FIG. 3 is a bottom view thereof;

FIG. 4 is a front view thereof;

FIG. 5 is a rear view thereof;

FIG. 6 is a left side view thereof;

FIG. 7 is a right side view thereof;

FIG. 8 is a top, front, left perspective view of the storage locker of FIGS. 1-8, shown in a closed position;

FIG. 9 is a top view thereof;

FIG. 10 is a bottom view thereof;

FIG. 11 is a front view thereof;

FIG. 12 is a rear view thereof;

FIG. 13 is a left side view thereof;

FIG. 14 is a right side view thereof; and,

FIG. 15 is a top, front, left perspective view of the storage locker of FIGS. 1-8 in an open position, shown with exemplary environment.

The broken lines shown in FIGS. 1-14 depict portions of the storage locker that form no part of the claimed design. The remaining broken lines in the form of a weight rack and other components in FIG. 15 depict environmental subject matter and form no part of the claimed design.

1 Claim, 10 Drawing Sheets
